(57) **CLAIM**

The ornamental design for a bracket for a modular structure as shown and described.

DESCRIPTION

FIG. 1 is a top view of a bracket for modular structure; FIG. 2 is a bottom view of the bracket for modular structure; FIG. 3 is a left side view of the bracket for modular structure;

FIG. 4 is a right side view of the bracket for modular structure;

FIG. 5 is a front view of the bracket for modular structure; the rear view being a mirror image thereof, therefore not shown;

FIG. 6 is a front perspective view from a left-side of the bracket for modular structure;

FIG. 7 is a rear perspective view from a left-side of the bracket for modular structure;

FIG. 8 is a front perspective view from a right-side of the bracket for modular structure;

FIG. 9 is a rear perspective view from a right-side of the bracket for modular structure; and,

FIG. 10 is a perspective view of the bracket for modular structure shown in an environment of use.

The broken lines shown in FIG. 10 are for purposes of illustrating environmental subject matter only and form no part of the design.

1 Claim, 10 Drawing Sheets
